UNITED STATES PATENT OFFICE

147,231

DESIGN FOR A COUNTER DISPLAY CASE

Julian G. Everett, Dobbs Ferry, N. Y., assignor to American Chicle Co., Long Island City, N. Y., a corporation of New Jersey

Application December 7, 1944, Serial No. 116,788

Term of patent 14 years

(Cl. D80—9)

To all whom it may concern:

Be it known that Julian G. Everett, a citizen of the United States, residing in Dobbs Ferry, county of Westchester and State of New York, has invented a new, original, and ornamental Design for a Counter Display Case, of which the following is a specification, reference being had to the accompanying drawing, forming part thereof.

The figure is a perspective view of a counter display case showing my new design.

I claim:

The ornamental design for a counter display case, substantially as shown.

JULIAN G. EVERETT.
